COMPRESSIBLE FLUID CONTROL MEANS
FOR TOILET FLUSH TANKS

Frank E. Wilt, San Diego, Calif.

Application October 30, 1950, Serial No. 192,862

6 Claims. (Cl. 4—43)

1

My invention relates to a compressible fluid control means for toilet flush tanks, and the objects of my invention are:

First, to provide a means of this class wherein a siphon control mechanism controls the flushing of water from a toilet flush tank, whereby valves and other wearing parts are eliminated;

Second, to provide a means of this class in which an auxiliary air chamber continually maintains an air supply for the air lock of the siphon in connection therewith, which insures proper functioning of the siphon when operated and prevents the air from escaping from said air lock during flushing operations of a conventional flush tank in which said siphon is installed;

Third, to provide a compressible fluid control means for toilet flush tanks wherein an auxiliary air chamber is vertically movable within the tank and below the normal water level of the tank providing for a pressure change in the air lock for starting the siphon when the auxiliary chamber is raised near to the upper level of the water in the tank;

Fourth, to provide a compressible fluid control means for flush tanks having a siphon flush tube therein, provided with an adjustable siphon vent tube communicating with the interior thereof, adapted to break the siphon within the siphon tube at the proper level within a toilet flush tank and prevent the water level from reaching the inlet level of the siphon, whereby quiet operation of the siphon is insured as it finishes draining the water from the flush tank to the desired level; and also controls the amount of water which reaches the toilet bowl for after-fill, and the amount of water which returns to seal the intake end of the siphon tube;

Fifth, to provide a compressible fluid control means for flush tanks of this class which provides very rapid and voluminous flow of water from a toilet flush tank, insuring efficient flushing of a toilet bowl;

Sixth, to provide a compressible fluid control means for toilet flush tanks in which maintenance costs are reduced to a minimum and which saves considerable water; and

Seventh, to provide a compressible fluid control means for toilet flush tanks of this class which is very simple and economical of construction, efficient in operation, and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawings and to the characters of reference thereon, forming a part of this application, in which:

2

Fig. 1 is a top or plan view of my compressible fluid control means for toilet flush tanks, shown positioned in a tank of conventional proportions; Fig. 2 is a front elevational view thereof, showing portions of the tank and the flushing means broken away and in section to amplify the illustration; and Fig. 3 is an enlarged fragmentary sectional view, taken from the line 3—3 of Fig. 2.

10 Similar characters of reference refer to similar parts and portions throughout the several views of the drawings.

The tank 1, float 2, float valve 3, levers 4 and 5, link 6, movable air chamber 7, guide rod 8, 15 siphon tube 9, siphon vent tube 10, baffles 11 and 12, chain 13, and the bracket 14, constitute the principal parts and portions of my compressible fluid control means for toilet flush tanks.

The tank 1 is a hollow, substantially rectangular tank of substantially conventional proportions. This tank 1 is provided with an outlet tube 1a cast in the bottom of the tank, as shown in Fig. 2 of the drawings. This outlet tube 1a is adapted to be connected with a conventional toilet bowl in the conventional manner. The siphon tube 9 extends upwardly into the tank nearer to the uppermost water level A, as shown by dash lines in Fig. 2 of the drawings, and this tube 9 extends downwardly in angular relationship laterally of its vertically extending portion, and is open at its intake end 9a, which is slightly spaced from the bottom 1c of the tank 1. The baffle 11 is an angularly disposed inverted V-shaped in cross-section structure, as shown in Fig. 2 of the drawings, and extends continuously from the inner side 1e to the inner side 1f of the tank 1, and it is sealed along said inner sides 1e and 1f by fusion, or the baffle 11 may be cast therein, as desired.

20 This baffle 11 is provided with an opening 11a in which the downwardly extending open end portion 9a of the siphon tube 9 is sealed. It will be noted that this baffle 11 is provided with an upwardly inclined portion 11b, which extends

25 along the lower side of the upwardly extending portion of the siphon tube 9, and is also provided with a downwardly extending portion 11c, having a lower edge 11d, which terminates in slight spaced relationship from the bottom 1c of the tank 1 near to the same level as the open ends 9a of the siphon tube 9. The baffle 12 as shown in Fig. 2 of the drawings, extends from the inner side 1e to the inner side 1f of the tank 1, and is sealed along the walls or may be cast

30 therein, as desired, and this baffle 12 is sealed in fluid-tight relationship with the bottom 1c of the tank 1, and extends upwardly to its upper terminus edge 12a in certain spaced relationship with the baffle 11, directly below the uppermost portion of the siphon tube 9.

The siphon vent tube 10 communicates with the uppermost portion of the siphon tube 9 and extends downwardly to a position at its lower end 10a, which is slightly above the lower end 9a of the siphon tube 9. The movable air chamber 7 is provided with a bell-shaped hollow head portion 7a, which communicates with a hollow tubular flexible air conductor 7b connected to the baffle 11 at its uppermost portion above the edge 12a of the baffle 12, providing an air passage inter-communicating with the bell-shaped head 7a of the movable air chamber 7, and the upper interior of the air lock chamber within the baffle 11.

The movable air chamber 7 is provided with an open downwardly converging skirt portion 7c having a guide member 7d fixed therein, and extending diametrically thereof through which the guide rod 8 extends. Thus, the movable air chamber 7 is vertically slidably mounted on the guide rod 8 which is fixed at its lower end to the bracket 14, held in place near the lower portion 1c of the tank 1, by means of the jamb nuts 3a on the water inlet tube 3b, communicating with the conventional valve 3 which is controlled by the float 2, normally positioned at the location shown in Fig. 2 of the drawings, near the water level A. The movable air chamber 7 is connected to the lever 5 by means of the chain 13. The lever 5 is pivotally mounted on a pin 5a in the side wall 1f of the tank 1, and the link 6 pivotally inter-connects the lever 5 with the outer side of the wall 1f of the tank 1.

It will be noted that the upper chamber portion 11e, formed by the baffle 11, provides a compressed airlock chamber, which tends to maintain the water levels substantially as shown in Fig. 2 of the drawings.

The operation of my compressible fluid control means for flush tanks is substantially as follows:

The movable air chamber 7, at its head portion 7a, is provided with compressed air therein, which is compressed in accordance with the column of water thereabove, and through the connector 7b this compressed air communicates with the interior of the airlock compression chamber 11e, at its uppermost portion. When the lever handle 4 is pivoted about the axis of the shaft 4b, the lever 4a moves the link 6, together with the lever 5, upwardly, causing the chain to raise the movable air chamber 7 along the guide rod 8. As the head portion 7a of the movable air chamber 7 passes upwardly in the water toward the level A, the pressure in the head portion 7a of the movable air chamber 7 decreases, causing a corresponding decrease in the pressure in the compressed air lock chamber 11e. Decrease in the pressure within the movable air chamber 7 is caused by decrease in the head of water thereabove when the movable air chamber 7 is raised toward the upper level A, as indicated by broken lines in Fig. 2 of the drawings.

When the air pressure is thus lowered within the movable air chamber 7 and the compressed air lock chamber 11e, the water at the level B, acted upon by the head of the water thereabove through said chamber 11e, passes upwardly in the siphon tube 9 and downwardly through the outlet tube 1a. Concurrently, water passes beneath the lower edge 11d of the baffle 11, and over the upper edge 12 of the baffle 12 to the open lower end 9a of the siphon tube 9. When the water reaches the lower end of the siphon vent tube 10, the siphon in the siphon tube 9 is broken, which occurs before the water passes

downwardly to a position coinciding with the end 9a of the siphon tube 9, preventing suction noise and the exhaustion of the water seal at the open end 9a of the siphon tube 9.

It will be noted that the movable air chamber 7 is balanced sufficiently heavy to gravitate to the bottom of the tank 1, after water in the tank flushes down a few inches, and remain there during flushing and the time the water builds up to the level A and the control of the float 2. During the time the water is filling the tank 1 by means of the conventional valve 3, operated by the float 2, water rising upwardly in the baffle 11 causes compression of air in the air chamber portion 11e, and correspondingly causes a raise of air pressure within the movable air chamber 7. When the pressure rises to a predetermined value, the level of the water at the dash line B is established, and the tank is again ready for flushing.

It will be here noted that the siphon breaking action of the tube 15 connected to the chamber 11e has substantially the same effect as the tube 10.

The lower open end of the movable air chamber 7 permits water to rise therein to a predetermined level until certain compression of air therein establishes the level at substantially the upper edge 12a of the baffle 12, all as shown best in Fig. 2 of the drawings. The conductor 7b is preferably made of rubber, or any other suitable material which is flexible, so that raising and lowering of the movable chamber 7 is readily accommodated without causing any loosening of the connections, or leakage between the movable air chamber 7 and the air compression chamber 11e.

It will be noted that when the tank 1 is flushed by raising the movable air chamber 7, the supply of air for the air compression chamber 11e passes into the movable air chamber 7, and does not become exhausted from the system by flow of water through the air compression chamber 11e over the upper edge 12a of the baffle 12. The volumetric displacement of air from the compression chamber 11e substantially fills the movable air chamber 7 down to its open skirt, and when the movable air chamber 7 is in its uppermost position it is lowered into the lower portion of the tank 1, by water pulled thereinto by vacuum caused by siphonic action within the tube 9. Thus, the air is caused to pass back into the air compression chamber 11e, so that exhaustion of the air from communicative relationship with the air compression chamber 11e is impossible, regardless of the operation of the lever handle 4.

It will be here noted that the siphon tube 9 provides an overflow for the tank 1 in the event the float valve 3 becomes inoperative.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. A tank, an outlet for said tank, a siphon tube extending upwardly into said tank from said outlet and communicating therewith, the opposite end of said siphon tube being slightly

spaced from the lower interior of said tank, air and water conductor means communicating with said opposite end of said siphon tube having an air compression chamber at the uppermost portion thereof above the lower end of said siphon tube spaced from the bottom of said tank, the opposite end of said air and water conducting passage means communicating with the interior of said tank near the lower portion thereof, a vertically movable air chamber in said tank open at its bottom portion and communicating with the interior of said air compression chamber at its upper portion, means for admitting water into said tank and maintaining the same at a predetermined level preliminary to flushing, a siphon vent tube communicating with the interior of said siphon tube near its uppermost portion and extending downwardly into spaced relationship with the bottom of said tank slightly above the terminus of said opposite end of said siphon tube.

2. In a device of the class described, a tank adapted to contain liquid therein, an outlet at the bottom portion of said tank, a siphon tube communicating with said outlet and extending upwardly in said tank and provided with a downwardly extending end internally of said tank slightly spaced from the bottom thereof, passage means defining the passage in said tank extending upwardly from said downwardly extending end of said siphon tube, a compression chamber near the upper end of said passage means, a second passage means extending downwardly from said compression chamber to a location near the bottom of said tank at the interior thereof, a vertically movable air chamber in said tank communicating with said compression chamber and having flexible means for conducting air intermediate said compression chamber and said movable air chamber.

3. In a device of the class described, a tank adapted to contain liquid therein, an outlet at the bottom portion of said tank, a siphon tube communicating with said outlet and extending upwardly in said tank and provided with a downwardly extending end internally of said tank slightly spaced from the bottom thereof, passage means defining the passage in said tank extending upwardly from said downwardly extending end of said siphon tube, a compression chamber near the upper end of said passage means, a second passage means extending downwardly from said compression chamber to a location near the bottom of said tank at the interior thereof, a vertically movable air chamber in said tank communicating with said compression chamber and having flexible means for conducting air intermediate said compression chamber and said movable air chamber, said movable air chamber open at its lower end and adapted to gravitate downwardly in said tank below the level of water therein, external means on said tank for raising said movable air chamber toward the upper surface of water therein.

4. In a device of the class described, a tank adapted to contain liquid therein, an outlet at the bottom portion of said tank, a siphon tube communicating with said outlet and extending upwardly in said tank and provided with a downwardly extending end internally of said tank slightly spaced from the bottom thereof, passage means defining the passage in said tank extending upwardly from said downwardly extending end of said siphon tube, a compression chamber near the upper end of said passage means, a sec-

ond passage means extending downwardly from said compression chamber to a location near the bottom of said tank at the interior thereof, a vertically movable air chamber in said tank communicating with said compression chamber and having flexible means for conducting air intermediate said compression chamber and said movable air chamber, said movable air chamber open at its lower end and adapted to gravitate downwardly in said tank below the level of water therein, external means on said tank for raising said movable chamber toward the upper surface of water therein, means for admitting water into said tank and means for controlling the level of water therein.

5. In a device of the class described, a tank adapted to contain liquid therein, an outlet at the bottom portion of said tank, a siphon tube communicating with said outlet and extending upwardly in said tank and provided with a downwardly extending end internally of said tank slightly spaced from the bottom thereof, passage means defining the passage in said tank extending upwardly from said downwardly extending end of said siphon tube, a compression chamber near the upper end of said passage means, a second passage means extending downwardly from said compression chamber to a location near the bottom of said tank at the interior thereof, a vertically movable air chamber in said tank communicating with said compression chamber and having flexible means for conducting air intermediate said compression chamber and said movable air chamber, said movable air chamber open at its lower end and adapted to gravitate downwardly in said tank below the level of water therein, external means on said tank for raising said movable chamber toward the upper surface of water therein, means for admitting water into said tank and means for controlling the level of water therein, a siphon vent tube communicating with said siphon tube at the interior thereof near the upper portion thereof and extending downwardly into spaced relationship with the bottom of said tank slightly above said lower end of said siphon tube.

6. In a device of the class described, a tank adapted to contain liquid therein, an outlet at the bottom portion of said tank, an air lock compression chamber providing a passage for water to said outlet and adapted to interrupt the flow of water therethrough when compression rises to a certain value therein, and a movable air chamber vertically movable in said tank, having flexible conductor means communicating with said air lock compression chamber, whereby elevation of said movable air chamber lowers the pressure therein and in said air lock compression chamber, permitting the flow of water therethrough to the outlet of said tank.
